HARP SWIVEL

Kornel Berger, Brooklyn, N. Y.

Application March 5, 1938, Serial No. 194,031

4 Claims. (Cl. 240—148)

The invention herein disclosed relates to shade supports and particularly to swivel mountings.

Objects of the invention are to provide a swivel mounting which will hold the shade in desired position on the harp and which at the same time can be readily shifted for purposes of adjustment and further to provide such a fixture in a relatively inexpensive, readily manufactured and assembled form of construction.

Additional objects and novel features of the construction by which such objects are attained are set forth and will appear in the course of the following specification.

The drawing accompanying and forming part of the specification illustrates various practical embodiments of the invention, but it will be appreciated that structure may be modified and changed all within the true intent and broad scope of the invention as hereinafter defined and claimed.

Fig. 1 is a broken elevation of a lamp with a lamp shade frame having a swivel of the present invention mounted thereon, the shade being indicated in broken lines.

Fig. 2 is a broken side elevation of the swivel fixture on an enlarged scale.

Fig. 3 is a side view of the fixture viewed at right angles to Fig. 2 and with the harp frame shown in section.

Fig. 4 is a bottom plan view with the wire of the harp frame broken away.

Fig. 5 is a broken sectional view as on substantially the plane of line 5—5 of Fig. 4.

Fig. 6 is a broken part sectional detail view of a modified form of the invention.

Fig. 7 is a broken side view illustrating a further modified form of the invention.

In the general view, Fig. 1, a lamp is indicated at 20, provided with a harp frame 21, carrying the swivel fixture which supports the shade frame 22.

As shown more fully in Figs. 2 to 5, the swivel fixture in this first embodiment of the invention consists of a cap piece 23, having diametrically opposite dependent or extended perforated lugs or ears 24, engaged about the harp frame 21, and a shade supporting stud 25, projecting up through the cap and having an extended base portion 26, in engagement with the frame, these two members being yieldingly thrust apart by a spring washer 27, interposed between the base of the stud and the bottom of the cap to thereby apply yielding frictional engagement to opposite sides of the frame.

The base or lower head portion of the stud is

shown as cross-grooved at 28, to fit the rounded surface of the wire in either one of two positions. This grooving provides additional surface for frictional engagement with the wire and also holds the stud against any possible rotation when the finial nut 29, Fig. 1, is turned down tightly over the upper threaded shank of the stud.

The spring washer 27, may be an ordinary split spring washer having sufficient spread and tension to hold the lower end of the stud firmly engaged with the wire and the lower encircling portions of the cap lugs 24, Fig. 3, firmly engaged with the opposite lower side of the wire. This provides a three point frictional engagement, with the stud bearing on the wire at an intermediate point between the two spaced cap lugs and results in a firm stable mounting of the fixture on the harp and one which at the same time permits the fixture to be easily rocked transversely over the wire. Because of such stability, this fixture is well adapted to support a larger and heavier form of shade than has heretofore been considered practicable.

In some cases, where it may be considered desirable to lock the swivel fitting in its position of adjustment, the wire constituting the harp may be roughened, toothed or ribbed as indicated at 30, Fig. 6, and, further, if considered desirable, either one, or both or all of the wire engaging elements be correspondingly roughened or toothed. Thus as in Fig. 6, one or both of the perforated cap lugs 24, may be toothed or similarly fashioned as at 31, to match the roughened part of the wire and the grooves in the flange or head 26, of the stud be toothed or roughened as indicated at 32. Also, in a construction of this sort, the wire may be left smooth and the biting effect of the stud or cap lug or lugs be relied upon to secure the swivel against unintended angular movement on the frame. In such forms of the invention where the engagement is something more than a purely frictional one, a lighter form of tensioning spring may be employed such as is indicated at 27a. Such a lighter form of spring is in fact desirable when full mechanical interlock between both members of the swivel and the wire is used as in Fig. 6, so that the holding effect may be relieved to some extent by pressing down on the cap when it is desired to effect an adjustment of the fixture. The interfitting teeth can be made quite fine and small, so that these adjustments will be practicable, the teeth in the illustration being possibly somewhat exaggerated in size for clarity of illustration.

The cap with its extended lugs, forms in effect a yoke engaging the supporting frame at separated points, with the shade supporting stud substantially at the center of the yoke structure, constituting on the whole a well balanced symmetrical form of fixture, in which the adjustable wire gripping parts are housed and largely concealed in the hollow of the cap. While the simple form of cap illustrated may be preferred, it is considered that the shape of this cap may be varied and while ordinarily considered as extensions of this cap structure, the parts 24, which engage the harp frame at separated points may be simply parts of a deep skirt extended from the body or top of the cap. Forming this member as a hollow cap, stiffens it sufficiently to stand the pressure exerted on the wire as well as constituting a housing enclosing or partly enclosing the spring tensioning means. Also, it will be appreciated that instead of having complete perforations, the lugs 24, or spaced sides of the yoke forming structure may be in the form of hooks engaging under the wire and open to permit quick sidewise engagement of the same on the wire.

Fig. 7 illustrates what may be considered as a modification of the first embodiment and in which the dependent holding lugs of the cap 23a, instead of having complete circular perforations, are open at one side to form hooks 49. These hooks may be faced in opposite directions as indicated, so that the cap can be engaged over the wire with a sidewise rotary or twisting movement. This construction has the advantage that it can be engaged over the harp after that frame has been bent up into its final shape, instead of having to be mounted on the wire before it is bent to the harp formation.

In Fig. 1, the perforated yoke or strap 55, connecting the lower ends of the harp wire is shown as roughened, toothed or knurled at 56, where it is engaged between the base of the lamp and the end of the lamp socket 57, so as in effect to form an interlocking clamp between the lamp base and the socket, thus to prevent turning of the socket after the parts have been set up tightly. The harp is thus made to hold the lamp socket against rotation and thus to serve to prevent the socket turning around to carry the switch key or button 58, out of its desired position on the lamp.

The flat cap form of the device illustrated has

the special advantage of providing a relatively wide flat base for firmly supporting large size or heavier lamp shade frames. The arrangement of the spring washer 27, between the underside of the cap and a flange 26 on the lower end of the stud, as in Fig. 5, provides a desirable frictioning of the swivel on the so-called harp frame, but this fundamental combination may be varied to suit special circumstances and the parts may be otherwise modified, all within the true scope of the invention. Terms employed therefore are to be construed in a descriptive rather than in a limiting sense, except possibly as need for limitation will appear or may be necessitated from state of the prior art. 15

What is claimed is:

1. A harp frame and a shade supporting fixture swivelled thereon and comprising a cap having dependent hooks engageable sidewise over the harp frame, a stud and means for exerting yielding frictional holding engagement with said frame. 20

2. A harp frame and a shade supporting fixture swivelled thereon and comprising a cap having dependent oppositely projecting hooks engaged over said frame, a stud having a shank portion projecting up through said cap and a head portion engaged with said frame and spring means interposed between said head portion and the cap for yieldingly thrusting said head into 30 frictional holding engagement with the harp frame.

3. A harp frame and a shade supporting fixture swivelled thereon, comprising a cap having dependent lugs in swivelled engagement with 35 said frame, a stud projecting from said cap and yielding holding means confined within said cap by said harp frame.

4. In combination, a wire harp frame, a yoke having perforated dependent lugs at opposite edge portions of the same embracing the wire of said harp frame at separated points and frictionally engaging the wire at the inner side of the frame, a lamp shade stud projecting from the intermediate portion of said yoke between 40 said dependent wire frame engaging lugs and means for applying a yielding frictional thrust to said wire frame in line with said stud at a point intermediate and at the opposite outer side of the wire engaged by said wire embracing lugs. 45
